UMBRELLA

Filed Nov. 26, 1928

UNITED STATES PATENT OFFICE

RAYMOND A. TEEL, OF GLENOLDEN, PENNSYLVANIA

UMBRELLA

Application filed November 26, 1928. Serial No. 322,055.

This invention relates to umbrellas and more especially to the construction of the frame of an umbrella.

Heretofore it has been the general practice to connect the ribs and stretchers to each other and to the rod by means of pivot pins and wires. The wires have been used on the sleeve and top notch and when one of them has become broken all of the parts engaged thereby have been released. This and other disadvantages have been present where umbrellas have utilized these old forms of connecting means.

It is an object of the present invention to improve upon the connections between the movable parts of an umbrella by providing ball and socket joints which can be easily made, readily assembled, and will hold the parts together securely.

Another object is to provide connections which are compact and do not add objectionably to the bulk of the umbrella when closed.

With the foregoing and other objects in view which will appear as the description proceeds the invention resides in the combination and arrangement of parts and in the details of construction hereinafter described and claimed it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is an elevation of a portion of the frame of an umbrella having the present improvements.

Figure 2 is an enlarged section on line 2—2, Figure 1.

Figure 3 is a section on line 3—3, Figure 2.

Figure 4 is an enlarged section on line 4—4, Figure 1.

Figure 5 is a section on line 5—5, Figure 4.

Figure 6 is an elevation showing the outer side of one of the connections between a rib and a stretcher.

Figure 7 is a view showing the opposite side of said connection, said figure being an enlarged section on line 7—7, Figure 1.

Figure 8 is a section on line 8—8, Figure 7.

Figure 9 is an inside elevation on a large scale of a portion of one of the ribs.

Figure 10 is a section on line 10—10, Figure 9.

Figure 11 is an elevation showing one side of the coupling sleeve used on the rib.

Figure 12 is an end elevation of said sleeve.

Figure 13 is a bottom plan view of a portion of one of the stretchers showing the ball at one end thereof.

Figure 14 is a side elevation of the structure shown in Figure 13.

Referring to the figures by characters of reference, 1 designates the rod of the umbrella provided at one end with a top notch 2 having an annular concavo-convex flange 3 the outer edge portion of which is provided with regularly spaced V-shaped ears 4.

Slidably mounted on the rod 1 is a sleeve 5 or runner provided at one end with a collar 6 having an annular concavo-convex flange 7 along the outer edge of which are regularly spaced tapered ears 8.

Seated against the concave face of the flange 7 are balls 9 molded on or clamped upon the spread terminals 10 of the flattened reduced ends 11 of longitudinally channelled stretchers 12. The ears 8 are bent over and between the balls as shown in Figure 5 so as to hold said balls assembled with the flange 7 and to keep the stretchers properly spaced apart.

The ribs 13 are channelled longitudinally as ordinarily and each is flattened and reduced at one end as shown at 14 where it is provided with a ball 15. The balls of the several ribs bear upon the concave face of flange 3 and are held thereto by the ears 4 which, as shown in Figure 3, are bent inwardly and serve to hold the ribs properly spaced.

At an intermediate point each of the ribs 13 has its channel slightly enlarged as shown at 16. This enlarged portion is seated in the laterally bulged intermediate portion 17 of a sleeve 18 which, as shown in Figures 8 and 12, is seated in the channel in the rib and has side flanges 19 which lap the outer surface of the rib. That portion of the sleeve

in the channel is shaped at its center to form a socket member 20 having a slot 21.

In assembling this sleeve with the rib the ball 9 at the outer end of the stretcher 12 is placed between opposed portions of the socket 20 after first spreading them apart at the slot 21. Said opposed portions are then drawn together to the normal positions shown in Figure 11 and the flanges 19 are 10 bent back of the rib as shown in Figure 8. Thus the ball on the stretcher will be held securely to the rib and as it is also seated in the enlargement 16, the sleeve will not become displaced longitudinally of the rib. The slot 15 21 will allow the stretcher to swing therein relative to the sleeve.

The several parts of the frame can be readily assembled, as will be obvious, and by reason of the construction of the connections, said parts will be held together securely, will work freely, and will permit the parts to lie compactly when the umbrella is closed.

What is claimed is:

1. In an umbrella the combination with 25 a rib channeled longitudinally, said channel being enlarged at a point between its ends to constitute a concave bearing, of a sleeve fitted in the channel and having an integral socket portion intersected by a slot, the side portions of the sleeve embracing the rib, a stretcher mounted to swing within the slot, and a ball on the stretcher movably mounted within and retained by the socket portion and the concave surface of the rib.
2. In an umbrella the combination with a 30 rib channeled longitudinally, of a sleeve embracing the rib having an integral socket portion closed by the rib, there being a slot intersecting that portion of the socket remote from the rib, and a stretcher extending through the slot and anchored at one end in the socket.
3. In an umbrella the combination with a 35 rib channeled longitudinally, of a sleeve embracing the rib, having an integral socket portion closed by the rib, there being a slot intersecting that portion of the socket remote from the rib, a stretcher extending through the slot, and a ball on the stretcher anchored in the socket, said socket being disposed within the channel in the rib.

In testimony that I claim the foregoing as my own, I have hereto affixed my signature.

55
